DUMPING DOOR FOR RAILWAY CARS AND THE LIKE

Original Filed May 15, 1925

Inventor:
Argyle Campbell

George D. Haught
Hisatty

UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMPING DOOR FOR RAILWAY CARS AND THE LIKE.

Original application filed May 15, 1925, Serial No. 30,416, now Patent No. 1,635,253, dated July 12, 1927.
Divided and this application filed August 6, 1926. Serial No. 127,546.

My invention relates to improvements in dumping doors for railway cars and the like.

This application is a division of my pending application 30,416, for improvements in 5 dump cars, filed May 15, 1925, now Patent Number 1,635,253, granted July 12, 1927.

An object of my invention is to lighten the weight of car doors by providing means whereby the strength-giving qualities of embossments or corrugations are continued beyond the end of the said embossments by 10 means of beam extensions.

Another object of my invention is to strengthen a door formed of a metallic plate 15 by embossments so disposed as to permit of shovelling between the said embossments and permit the discharging material to flow readily over said embossments when the doors are in open position.

20 A further object of my invention is to rigidify the door plate by embossments disposed above the plane of the door, and to further dispose and secure rigidifying or stiffening members on the underside of the door in such 25 relation to the embossments that the door will be strengthened to resist longitudinal bending.

Other and further objects of the invention will more fully and clearly appear from the 30 description and claims hereinafter following.

In the drawings Fig. 1 is a plan view of a door embodying my improved construction. Fig. 2 is a front elevational view of the door shown in Fig. 1. Fig. 3 is a vertical sectional view through the door, taken on a line corresponding substantially to the line 3—3 of Fig. 1, and Fig. 4 is a sectional view taken through the door on the line corresponding to line 4—4 of Fig. 1.

40 The dumping door is preferably formed of metal as shown, having a series of rigidifying embossments 20 in the form of corrugations or indentations, preferably pressed above the plane of the door plate, and extending 45 from the hinged end of the door towards the free edge thereof, and preferably the margins of the door are downwardly flanged at the side edges as at 21—21, and at the front and rear edges as indicated at 22 and 23. 50 Each door is adapted to be pivotally mounted at its rear edge by means of hinge straps 24 on the door, which extend through the rear flange 23 thereof, each strap 24 being formed with a hinge eye 25 through which a

55 pivot pin is adapted to extend to connect the same with the car structure. The hinge straps 24 adjacent the side edges of the door are connected with the door and with longitudinally extending reinforcing angle-shaped members 26 which extend towards the free 60 edge of the door and connect with the upper flange of a Z bar 27, which extends from side edge to side edge of the door as shown.

The outer or swinging edge of the door is supported from the car through the medium 65 of suitable door supporting means of the character shown in my pending application Serial No. 30,416, filed May 15, 1925, and indicated at 270, which are adapted to engage the outer ends of door beams A—A. Each 70 of the beams A—A extends in vertical alignment with one of the corrugations 20 inwardly beneath the door for an appreciable distance, and terminates intermediate the 75 ends of its corresponding corrugation. Each beam A is preferably formed of a U-shaped member having depending flanges 28—28, lying normal to the plane of the door, and a web portion 29, which lies against the door plate and is secured thereto by a rivet 30 at 80 the end of the adjacent corrugation. Each beam A, and its corresponding corrugation, are adapted to extend across the vertical plane of the Z-shaped member 27, and in 85 order to preserve continuity of reinforcement for both the longitudinal and transverse members, the U-shaped portion of the member is flattened out where it passes across the vertical plane of the Z-bar 27, thereby 90 presenting a widened portion on either side of the corrugation as indicated at 31, said portion being adapted to receive rivets 32, whereby connection is effected with the door and also with the Z-bar 27, said rivets being 95 disposed on either side of the adjacent corrugation 20.

The Z-bar 27, where it crosses the flattened portion 31 of the beam A, is crimped as indicated at 33—33. The transition from the U-shaped section to the flat plate section of 100 each beam is effected without tearing of the metal by means of a flare and twist of the flange as indicated at 34, said transition from the one section to the other being effected within the limits of the corrugation. Each beam A extends across the free edge of the door and curves downwardly and outwardly 105 in the form of a reverse curve as indicated

at 35, and thereafter extends outwardly in a substantially horizontal plane beyond the car side. The upper portion of the reverse curve 35 of the beam A extends slightly beyond the free edge of the door and across the plane of the flange 22, which is flared outwardly adjacent each of said beams as indicated at 36, to conform to the curvature of the said beam, and a rivet 37 connects the said flared portion of the door flange with the curved portion of the beam A.

This arrangement of door bracing is particularly effective, as the full rigidifying effect of the corrugations is utilized and particularly so, because the Z-bar stiffener provides a strong reinforcement cross-wise of the corrugations, which effectively serves to brace the corners of the door against downward bending, and inasmuch as the hinge beams 26 are also connected to the Z-bar 27 there is thus presented a continuous framework reinforcing the door adjacent the side and front margins thereof. The body of the door within such frame work is reinforced by the embossments 20 with which the beams A—A, for prolonging the rigidifying effect of the embossments beyond the free edge of the door, cooperate to provide a door of exceptional strength.

The embossments 20 are preferably disposed in parallel relation and formed of truncated shape with flat tops 38 joined to the main body of the plate by sloping connecting webs as indicated at 39 and 40. The rear longitudinally extending connecting webs 39 of the various embossments are disposed at a lesser slope than the remaining webs thereby permitting material to readily flow above the embossments when the door is in open position. The various embossments 20 are separated by intervening flat floor sections 41 which are disposed in substantially the main plane of the door and are preferably formed of wider extent than the adjacent embossments thereby forming relatively wide valleys having sufficient area to prevent the retention of material and moisture, and also permitting the securing of the underlying beam member 27 to the door plate by a plurality of rivets as indicated at 42.

In order to further strengthen each beam A and secure the same to the door beam 27, connecting brackets 43 may be utilized. Each bracket 43 is preferably in the form of a U-shaped member secured to the flat portion of beam A directly as at 44, and also to the depending flanges 28 as at 45—45. At its inner end said bracket is flanged on either side thereof as indicated at 46—46 and has the flanges secured to the vertical flange of the Z-bar by means of rivets 47.

Adjacent its outer end, one of the flanges 28 of each beam A is flared inwardly towards the other flange for a short distance, presenting a curved ledge 48 disposed substantially

in the plane of the door, and is preferably welded to the other flange as indicated at 49, said ledge 48 being adapted to have suitable door supporting means seat thereunder.

While I have herein shown and described what I now consider the preferred manner of carrying out my invention, the same is merely illustrative and I contemplate all changes and modifications that come within the scope of the claims appended hereto.

What I claim is:

1. In a dump door, a corrugation extending from the hinged edge of the door towards the free edge thereof; and a beam member secured to the door, said beam member being disposed in the vertical plane of the said corrugation, and adapted to effect continuity of the strengthening effect of said corrugation beyond the limits of the same.

2. In a dump car, the combination with a metallic car door having a plurality of corrugations extending from the hinged edge of the door towards the free edge thereof; of additional beam members disposed in the vertical planes of said corrugations and adapted to continue the strength-giving qualities of the corrugations beyond the free edge of the door.

3. In a dump car door, the combination with an embossment extending above the plane of the door; of a member disposed in vertical alignment with the said embossment, said member being secured to the door on either side of the said embossment and extending beyond the free edge of said door.

4. In a dump car, the combination with a plurality of rigidifying corrugations formed integrally with the door, said corrugations terminating a short distance from an edge of the door; and extensions adapted to continue the strength-giving qualities of the corrugations beyond said edge of the door, each of said extensions being disposed in vertical alignment with a corrugation and secured to the door within the limits defined by the related corrugation, and at each side thereof.

5. In a dump car door, the combination with a corrugation formed integrally in the door plate; of a beam member disposed in the vertical plane of the corrugation and adapted to provide a continuation of the strengthening qualities of the corrugation beyond the end of said corrugation.

6. In a dump car door, the combination with a U-shaped member secured to the under side of the door and extending beyond an edge thereof, said U-shaped member having the flanges thereof disposed substantially normal to the plane of the door, one of said flanges having a portion near the end thereof flared inwardly toward the other flange of the U-shaped member to form a ledge extending substantially in the plane of the door; said ledge being adapted to have door retaining means seat beneath the same.

7. In a dump car door, the combination with a series of embossments; of a beam extending cross-wise of the said embossments; means extending in prolongation of the embossments, said means extending across said beam and secured thereto, said means including a beam member having a portion thereof in the form of a flat plate secured to the first named beam and to the door. 65
- 10 8. In a dump car, the combination with a rigidifying corrugation; of a beam member extending beyond the free edge of the door, said beam member having a portion formed of U-shape and having another portion there- 70
15 of formed of flat plate, said flat plate having portions thereof disposed on either side of the corrugation and thereby secured to the door. 75
- 20 9. In a dump car door, a corrugation ex- tending above the plane of the door; a beam disposed below the plane of the door, said beam being disposed in vertical alignment with the corrugation and formed with a flat section having portions disposed on either 80
25 side of the said beam and secured to the door, said beam including a U-shaped portion project- ing beyond the edge of the door, said U- shaped portion merging into the flat plate within the limits of the corrugation. 85
- 30 10. In a dump car door, the combination with a reinforcing member secured to the underside of the door; of a series of embossments extending across the reinforcing member, the raised portion of each embossment 90
35 including a flat section of extended area, said raised embossments being separated from each other by intervening flat floor sections lying in the plane of the door, said last named flat floor sections being of greater area than the raised flat sections of said embossments. 95
- 40 11. In a dump car door adapted to be hinged at one end and supported at the op- 100
45 posite end, the combination with a metallic plate having a plurality of parallel emboss- ments formed therein to reinforce the plate intermediate the hinged and supported ends, said embossments being formed with flat tops joined to the main body of the plate by sloping webs, those webs extending between 105
50 the hinged end of the door and the flat tops of the embossments being formed of a flat- ter slope than the remaining webs, thereby permitting discharging material to flow over the embossments when the door is in open position. 110
- 55 12. In a dump car door, the combination with a reinforcing member secured to the un- 115
60 der-side of the door; of a series of emboss- ments raised above the plane of the door and extending across the vertical plane of said member, said embossments being separated from each other by intervening flat floor sec- tions lying in the main plane of the door; securing means extending through the said intervening flat floor sections and underly- 120
65 ing reinforcing member; and extension ele- ments secured to the under-surface of said door and to said reinforcing member in ver- tical alignment with certain of said emboss- ments, said extension elements projecting be- 70
75 yond the free edge of the door. 80
13. In a dump car door, the combination with a metallic plate having a plurality of parallel reinforcing embossments formed therein, said embossments being formed with flat tops joined to the main body of the plate by sloping webs, said embossments being separated from each other by intervening flat floor sections lying in the main plane of the plate; and an underlying reinforcing member 85
80 extending across the various embossments and secured to the said intervening flat floor sections. 90
14. In a dump car door, the combination with an embossment extending above the plane of the door; of a member disposed in vertical alignment with the said embossment, said member being secured to the door; and door supporting means co-operating with said member to maintain the door in closed position. 95
15. In a dump car, the combination with a metallic car door having a plurality of cor- rugations extending from the hinged edge of the doors towards the free edge thereof; of additional beam members disposed in the vertical planes of said corrugations and adapted to continue the strength-giving qualities of the corrugations beyond the free edge of the door, and door supporting means co- 100
